UNITED STATES PATENT OFFICE.

GIUSEPPE PEPÉ, OF WALWORTH, COUNTY OF SURREY, ENGLAND.

APPARATUS FOR DRYING STEREOTYPE-MATRICES.

SPECIFICATION forming part of Letters Patent No. 334,544, dated January 19, 1886.

Application filed July 13, 1885. Serial No. 171,447. (No model.) Patented in England May 20, 1884, No. 7,959.

To all whom it may concern:

Be it known that I, GIUSEPPE PEPÉ, a subject of the King of Italy, residing at 55 Beresford Street, Walworth, in the county of Surrey, England, stereotyper, have invented certain new and useful Improvements in Apparatus for Drying Stereotype Matrices, (for which I have received Letters Patent in Great Britain, No. 7,959, dated May 20, 1884,) of

10 which the following is a specification.

For this purpose I employ a hollow drum, upon the exterior surface of which I arrange a number of hinged clamping-frames to hold the matrices in contact with the drum. The drum 15 is made with projections or ribs to act in combination with hollows in the clamping-frames, or vice versa. The drum is mounted in a casing with capability of revolving upon a hollow axle, through which steam is introduced into 20 the interior of the drum.

At some convenient part or parts of the apparatus I arrange a fire, and I conduct the products of combustion therefrom through a flue carried partially or entirely around the exterior of the drum and near to the stereotype-matrices clamped thereon. In the casing I 25 advantageously employ an outlet or outlets for the escape of moisture driven off from the stereotype-matrices.

30 The fire or fires may be employed to melt the metal required to produce the stereotype, and with this object I arrange one or more melting-pots at some convenient part of the apparatus.

In some cases I dispense with a special fire 35 for the apparatus, and pass through the flue around or partly around the drum heated air or products of combustion obtained from other sources.

By the use of my improved apparatus the 40 production of stereotype-matrices for newspaper and other printing is very greatly facilitated and cheapened, as the time employed in drying the same is greatly reduced, while by the peculiar form and action of the apparatus 45 the buckling or unequal drying and shrinkage of the matrices is prevented.

My invention also enables me to retain in 50 position in the matrices the pieces of card-board employed to retain the form of the white spaces, so that when the matrices are dried they require only little finishing. This effect is obtained by clamping the matrices onto the re-

volving drum with their backs toward the drum, the pieces of card-board in the white spaces being also in contact with the drum, 55 and thereby held in position during the drying operation; and in order that my said invention may be more clearly understood and readily carried into effect, I will proceed, aided by the accompanying drawings, more fully to 60 describe the same.

In the drawings, Figure 1 is a vertical section, and Fig. 2 is a sectional plan, of apparatus constructed according to my invention. Figs. 3, 4, and 5 are detail views, and Figs. 6 65 and 7 are views drawn to a larger scale showing a piece of card-board in position to form a white space.

a is a hollow drum, upon the exterior surface of which are arranged a number of hinged 70 clamping-frames, b, to hold the matrices in contact with the drum a. The drum a, as shown at Fig. 5, is formed with grooves or hollows a', to act in combination with the sides of the clamping frames b, in order to facilitate 75 the holding of the matrices in position. The drum a is provided with hollow necks or axes a², which are mounted in bearings c on the sides of the casing c, and through stuffing-boxes a³ on the ends of such necks or axes a² 80 are passed stationary pipes d e, steam being admitted into the drum through the pipe d, and passing away therefrom through the pipe e.

At some convenient part or parts of the apparatus I arrange a fire-place, f, and I conduct 85 the products of combustion from the fire therein through a flue, g, carried partially around the exterior of the drum a, as shown in the drawings, (or it may be entirely around the same,) and near to the stereotype-matrices clamped 90 thereon. In the casing c, I arrange outlets c² for the escape of moisture driven off from the stereotype-matrices, and such moisture is circulated by means of wings a⁹, and is drawn through such outlets c² by the draft in the flue g. 95

The fire or fires may be employed to melt the metal required to produce the stereotype, and with this object I arrange one or more melting-pots on the top of the fire-place f, or at some other convenient part of the apparatus. 100

The clamping-frames b are advantageously made, as shown, with outer bars, b', the end ones of which are connected together by cross-bars b². Such frames b are provided with

projections b^3 , which pass through eyes a^4 and act as hinges, while they are also provided with catches b^4 , which act, in combination with eyes or hooks a^5 , to hold the said clamping-frames, and consequently the matrices firmly against the cylinder a . The drum a in its interior is provided with cups a^6 , which act to lift the water of condensation, and on the same falling it is carried away by the steam through the trumpet-shaped pipe e' , fixed to the pipe e . Other suitable means may, however, be employed for carrying off or discharging the condensed water. The upper part of the casing c is hinged, so as to enable it to be thrown back into the position shown by dotted lines in Fig. 1, when it is desired to apply the matrices to or remove them from the cylinder a . At other times such upper hinged part of the casing b is placed in the position shown by the full lines.

The drum a is provided with a pulley, a^7 , by which, aided by a strap or band, it may be rotated during the drying operation, while it is also provided with a hand-wheel, a^8 , by which, when not driven by the band, it may be turned to the required position for placing the matrices thereon or removing the same therefrom.

At Figs. 6 and 7 I have represented the means advantageously adopted for retaining

the form of the white spaces. h represents the stereotype-matrix, which is clamped with its back toward the drum a , and i a piece of cardboard to form a white space, which is placed between the matrix and the drum a , and is connected to the back of the matrix, and is thereby held in position during the drying operation.

Having now particularly described and ascertained the nature of my said invention, and in what manner the same is to be performed, I declare that what I claim is—

1. The combination, in an apparatus for drying stereotype-molds, of a rotary drum, clamping-frames carried by said drum for the attachment thereto of the molds to be dried, and a surrounding casing for the circulation of air around said drum and the attached molds, substantially as herein described.
2. The combination of the rotary steam-heated drum a , the clamping-frames b , attached to said drum, the casing c , surrounding said drum and having outlets c^2 , and the flue partly surrounding said casing and communicating with the interior thereof through the outlets c^2 , substantially as herein described.

GUIDEPPE PEPÉ.
